OTIS W. STANFORD; OF LEBANON, OHIO.

Letters Patent No. 85,866, dated January 12, 1869.

IMPROVED BED-BOTTOM.

The Schedule referred to in these Letters Patent and making part of the same.

To whom it may concern:

Be it known that I, OTIS W. STANFORD, of Lebanon, Warren county, Ohio, have invented a new and useful Bed-Bottom; and I hereby declare the following to be a full, clear, and exact description thereof, reference being had to the accompanying drawing, making part of this specification.

This invention relates to a simple, cheap, and effective form of bed-bottom, consisting essentially of a series of arched or cambered slats, whose ends are sprung into and confined by sockets in a pair of cross-rails, into which sockets cushions, of India rubber, have been previously inserted.

Figure 1 is a perspective view of a bed-bottom embodying my invention.

Figure 2 is a longitudinal section through said bottom.

Figure 3 is a partial longitudinal section, showing a modification of my invention.

A A' are the side rails;

B B', the head and foot-rails;

C, central stretcher; and

D D', intermediate cross-rails, forming, collectively, a rectangular frame.

The head and foot-rails B B' have mortises or sockets b, to receive, first, cushions E, of India rubber, and next, the extremities of wooden slats F, formed of ash, or other highly-elastic timber, which slats are cut so much longer than the distance between the head and foot-rails as to acquire, when inserted in their sockets, the sprung or cambered form represented.

The intermediate cross-rails are preferably made sufficiently limber to yield slightly when the depres-

sion of a slat brings it in contact with the rail, as shown by dotted lines in fig. 2.

Prominent among several advantages of this over the customary slat-bottoms, are—

The bottom being permanently arched, and confined at its ends, is not liable to become sagged downward in the middle, as occurs with many other forms of bed-bottom—a tendency which entirely unfits them for properly supporting the human body.

Any depression of a slat, instead of causing it to sag throughout its length, as in the customary bottoms, is accompanied by a mere local depression, (see dotted line in fig. 2,) so that the bottom becomes self-adaptive to every flexure of the body.

The bottom being essentially of wood, can be made easily in any place, and at little expense.

It is remarkably light to handle, is easily repaired, and can be kept clean without difficulty.

In the modification shown in fig. 3, the foot-rail, instead of being framed permanently into the side rails, occupies slots therein, and is held in place by means of springs G.

I claim herein as new, and of my invention—

The combination, with the cambered slats F, of the springs or cushions E, arranged within the sockets b, supporting the ends of said slats, as represented and described, for the purposes set forth.

In testimony of which invention, I hereunto set my hand.

OTIS W. STANFORD.
